UNITED STATES PATENT OFFICE.

JOSEPH N. BECKER, OF RICHMONDVILLE, NEW YORK.

IMPROVEMENT IN TRESTLES FOR RAILWAYS.

Specification forming part of Letters Patent No. 148,023, dated March 3, 1874; application filed January 9, 1874.

To all whom it may concern:

Be it known that I, JOSEPH N. BECKER, of Richmondville, State of New York, have invented certain new and useful Improvements in Bridges and Trestles for Railroads; and I do hereby declare that the following is a description thereof, reference being had to the accompanying drawings forming a part of this specification, in which—

Figure 1 represents a perspective view of a section of a bridge or trestle embodying the improvements in this invention. Fig. 2 is a vertical view of the same. Fig. 3 is a cross-sectional view taken at line No. 1 in Fig. 2. Fig. 4 is a sectional view taken at line No. 2 in Fig. 2.

My invention relates to bridges and trestles for railroads; and consists in combining, with the usual sleepers of a bridge, shelving or sloping caps, placed between the ties, supporting the rails, and over the upper surfaces of the said sleepers, in such a manner that the apex of each cap may be about on a plane with the lower surface of the base of the rails, so as to form shelving surfaces immediately below the rail and above the sleepers, which will be capable of causing all coals dropping from the locomotive to immediately slide off, and thus prevent a lodgment of such coals on the said sleepers, or in the jointures or spaces between the same, as heretofore was liable to occur.

The object of this invention is to prevent the bridge or trestle from being fired by the burning coals which may accidentally fall from the locomotive in its passage over the same.

To enable others skilled in the art to make and use my invention, I will proceed to describe it with reference to the drawings and the letters of reference marked thereon, the same letters indicating like parts.

In the drawings, A A represent the usual sleepers or string-pieces of a bridge, supported by the usual bearing-beams, or posts or piers, in the ordinary manner. B B are the usual ties, having their bearings on the said sleepers. C C are the usual iron rails, supported by the ties, all of which are so

well known as to require no particular description.

Heretofore it has been the custom to leave the top surface of the timbers A A exposed, with their upper sides, beneath the rail, flat, and capable of receiving and retaining any substance that might fall on them. The said timbers are often arranged together in pairs, as shown, with their adjacent sides a little distance apart, so that a piece of any substance an inch or two in diameter would not be liable to pass through, but would find a lodgment between; and in case of the falling of a live coal from a passing locomotive, such lodgment on or between the timbers A A will, in many cases, fire the said timbers, and thus destroy the bridge. The same danger is connected with bridges made with lines of single timbers, or with lines of three timbers, as A A A' in Fig. 3.

In my improvement in bridges, I place over the upper surfaces of the sleepers A A, and between the ties B B, the caps D D, which caps may be made of wood or metal, and are so formed as to produce two sloping or shelving surfaces, a a, as shown in Figs. 1 and 3, which surfaces, commencing at the apex of each cap, slope downward and out past the outer sides of the timber or timbers A A, which they cover. The said caps are so placed in position that the apex of each will be about on a line with the lower surface of the base of the rail C, and beneath the same, so as to preclude all possibility of a lodgment of the coals between the rail and the caps on either side of the said rail.

In operation, these caps will, by their shelving surfaces, a a, cast off the coals falling on them; and though the said inclined surfaces are not necessarily required to be very great, as the slight jar caused by the passage of the locomotive and its tender will aid the coals in sliding off, yet I would give to the said surfaces as great an angle of inclination as the distance between the rail and the sleepers A would admit.

This invention, though simple and of but little expense in application, is effective for preventing the lodgment of the burning coals on the said timbers beneath the rail, and will

render the bridge or trestle safe from being burned through such a cause, and can be readily applied to all bridges or trestles constructed of wood, in the manner as above described.

Having described my invention, what I claim, and desire to secure by Letters Patent, is—

In railroad bridges or trestles, the caps D

D, made with sloping or shelving surfaces *a*, and placed over the usual sleepers, or equivalent timbers, A A, and below the rail C, substantially as and for the purpose set forth.

JOSEPH N. BECKER.
